United States Patent

Des. 237,028
Patented Oct. 7, 1975

237,028

SEAT

Philip L. Null, Maiden, N.C., assignor to
Null, Incorporated

Filed May 8, 1974, Ser. No. 468,015

Term of patent 14 years

Int. Cl. D6—01

U.S. Cl. D6—68

Fig. 1

Fig. 2

Fig. 3

Fig. 4

FIG. 1 is a front perspective view of a seat showing my new design incorporated in a chair;

FIG. 2 is a front elevational view thereof;

FIG. 3 is a side elevational view thereof;

FIG. 4 is a rear elevational view thereof;

FIG. 5 is a front perspective view of a seat showing my new design incorporated in a love seat; and

FIG. 6 is a front perspective view of a seat showing my new design incorporated in a sofa.

I claim:

The ornamental design for a seat, as shown.
